DANIEL M. SKINNER, OF SANDWICH CENTRE, NEW HAMPSHIRE.

Letters Patent No. 65,616, dated June 11, 1867.

IMPROVED PLATE-LIFTER.

The Schedule referred to in these Letters Patent and making part of the same.

TO ALL PERSONS TO WHOM THESE PRESENTS SHALL COME:

Be it known that I, DANIEL M. SKINNER, of Sandwich Centre, in the county of Carroll, and State of New Hampshire, have invented a new and useful or improved Implement for Lifting and Removing a Dish or Plate from a Stove Oven, or for supporting it while being inserted in an oven or in a stove or heating apparatus; and I do hereby declare the same to be fully described in the following specification, and represented in the accompanying drawings, of which—

Figure 1 is a top view,

Figure 2 a front view, and

Figure 3 a side elevation of it.

The whole implement is to be constructed of wire and in one piece, although it need not necessarily be so made, as it may be formed of two or more pieces of wire. In the first place the piece of wire of the proper length is to be bent around at its middle, so as to form it there in the shape of a spring, as shown at *a*, and with the two parts next thereto arranged in manner as shown at *b b*. Next each leg or part of the wire is to be again bent, as shown at *c*. Next it is to be curved or bent as represented at *d*. Next it is to be bent down at a right angle, or thereabouts, as shown at *f*. Next it is to be bent at an obtuse angle, as shown at *g*. Next it is to be bent again as seen at *h*. Next it is to be curved as shown at *i*. Next it is to be bent upward at a right angle, as shown at *k*. Next at an obtuse angle, as shown at *l*; and finally, the end is to be turned or hooked around the bend *e*. I would remark that the curve of each part *d* is to be quicker, that is, formed with a radius shorter than that of the curve of the part *i*.

When the implement is used it is to be seized by its handle portion *A*, and applied to the plate or dish so as to grasp it on opposite sides, and with its rim resting on either pair of the parts, *i i* or *d d*, of what may be termed the jaws *B B*.

I claim the plate-lifter made as described, viz., of a wire bent as shown at *a b c d f g h i k l*, so as to form the elastic handle portion *A* and two open jaws *B B*, as represented.

DANIEL M. SKINNER.
